FREE AND OPPOSED PISTON MOTOR COMPRESSOR UNIT

Raul Pateras Pescara, Paris, France

Application July 11, 1936, Serial No. 90,235
In Belgium July 13, 1935

10 Claims.

(CL. 230—56)

This invention relates to internal-combustion motor-compressor units of the free and opposed piston type, and more particularly to such units comprising at least two compression stages; and it relates still more particularly to multi-stage free piston motor compressors of the asymmetrical type, as hereinafter defined.

In my co-pending application Ser. Number 650,351, I disclosed certain improvements in internal-combustion free and opposed piston motor compressor units of the symmetrical type, meaning thereby such units comprising one or more pressure stages, each of which stages comprises two identical compressor cylinders symmetrical disposed at opposite ends of a common motor cylinder. Said improvements related mainly to the provision of pneumatic means adapted to supply the energy required to return the freely-reciprocating pistons, at the end of each working stroke, to their correct respective positions at the beginning of the next working stroke, regardless of the variations in the length of said working strokes. They consisted, namely, in providing three combined sources of energy for the return stroke: First, the expansive energy of the residual compressed gas remaining in the clearance space of the compressor cylinders, which energy supply is a negative linear function of the length of stroke; secondly, the energy supplied to the high-pressure pistons by the compressed gas delivered by the low-pressure stage to the high-pressure stage; and thirdly, the energy available from auxiliary pneumatic cushioning spaces permanently supplied with high-pressure compressed gas by the high-pressure stage; both the second and third energy supplies being positive linear functions of the length of stroke, and hence adapted to balance at all times the energy available from said first source, and so to render the total supply of return energy substantially constant, regardless of the variations in the length of the working strokes.

The main purpose of the present invention is to extend the application of the improvements disclosed in the above-mentioned co-pending application to multi-stage free and opposed piston motor compressors of the asymmetrical type—meaning thereby such units comprising at least two compression stages, each of which stages comprises only one compressor cylinder, instead

of two, as in the symmetrical type, the cylinders of successive compression stages being suitably disposed at opposite ends of the motor cylinder—for example, in a two-stage compressor unit, the low-pressure stage being at one end of said motor cylinder, and the high-pressure stage at the other end.

The principal object of my invention is to provide a multi-stage motor-compressor unit of the asymmetrical type, as hereinbefore defined, comprising combined pneumatic means adapted to supply energy for the return stroke of the motive pistons, and to substantially equalize the aggregate forces acting on the oppositely-reciprocating piston groups.

Another object is to provide a multi-stage motor-compressor unit as above, in which said combined pneumatic energy supplying means comprise: Firstly, a pneumatic cushion remaining in the clearance space of the low-pressure cylinder; secondly, the volume of partly-compressed gas delivered by each pressure stage to the next higher pressure stage—for example, in a two-stage compressor unit, by the low-pressure to the high-pressure stage which partly-compressed gas assists materially in the return of the piston; and thirdly, auxiliary pneumatic compensating means adapted to simultaneously supply the balance required for the return stroke of the motive pistons, and to equalize the aggregate forces acting on the oppositely-reciprocating piston groups, with a view to relieving the synchronizing linkages interconnecting said oppositely-reciprocating piston groups from any strains other than those due to their own inertia.

A further object is to provide a two-stage motor-compressor unit of the asymmetrical type, in which said auxiliary pneumatic compensating means consist of a single gas cushioning cylinder acting on the low-pressure compressor piston.

A still further object is to provide a two-stage motor-compressor unit of the type described, in which the combined pneumatic energy supplying means, as hereinbefore described, co-act to provide an amount of energy for the return stroke which is substantially constant, regardless of the variations in the length of the working stroke, and to further equalize, at least at one point of the working stroke, the aggregate forces acting on the oppositely reciprocating parts.

A still further object is to provide a two-stage motor-compressor unit of the type described, in which said combined pneumatic energy supplying means co-act to provide of energy for the return stroke which is variable, for varying lengths of the working stroke, within given predetermined lower and upper limits, and to further equalize, at least at one point of the working stroke, the forces acting on the reciprocating 10 parts.

A still further object is to provide a two-stage motor-compressor of the type described, in which the action of the above mentioned combined pneumatic means is adjusted by subjecting the 15 rear or inactive faces of the low and high-pressure compressor, pistons to gas pressures other than atmospheric.

A still further object is to provide a two-stage motor-compressor unit of the type described, in which the space between the two compressor pistons is inclosed within a casing, and all or part of said space is used to compress or store gas for motor scavenging purposes.

Other objects and advantages of my invention will appear to one skilled in the art, from the following description, with reference to the accompanying drawings, it being understood of course, that said description and drawings are given by way of illustration, only, and should not 30 be construed as limiting the scope of my invention.

In these drawings:

Fig. 1 shows diagrammatically, in longitudinal cross-section, a two-stage motor-compressor unit 35 embodying my invention;

Fig. 2 shows a diagram of the forces acting on the low-pressure compressor piston at all points of the working and return strokes;

Fig. 3 shows a similar diagram for the high-pressure compressor piston;

Fig. 4 a similar diagram for the auxiliary compensating cylinder.

Fig. 5 is a view similar to Fig. 1 of a modification of the invention.

In one of the preferred embodiments of my invention, I provide a motor cylinder 1 co-acting with two axially slidible motive-pistons 2₁ and 2₂ adapted to reciprocate in opposite directions within said cylinder; and I further provide low-pressure and high pressure compressor pistons 3₁ and 3₂, the first rigidly connected to motive piston 2₁ and the second to motive piston 2₂, said compressor pistons co-acting respectively with low-pressure and high-pressure cylinders 4₁ and 4₂. In order to equalize the forces acting respectively on the oppositely reciprocating assemblies comprising respectively motive and compressor pistons 2₁ and 3₁ and 2₂ and 3₂, and to supply the balance of energy necessary for the return 60 of the pistons, I provide an auxiliary compensating pneumatic cylinder 6 with co-acting piston 5 rigidly connected to compressor piston 4, and connect said compensating cylinder 6 to the delivery of the high-pressure compressor cylinder. This 65 is equivalent to applying to a fraction of the area of the low-pressure compressor piston a constant compensating super-pressure equal to the delivery pressure of the high-pressure stage.

In order to fulfill the different known requirements insuring maximum operating efficiency in multistage compressors, the following dimensional relations must be observed:

Assuming S₁ and S₂ to be respectively the surface areas of the low-pressure and high-pressure compressor pistons 3₁ and 3₂, and p₁ and p₂ to

be respectively the delivery pressures of the low-pressure and high-pressure stages, and p₀ the initial suction pressure, which is usually that of the atmosphere, it may readily be seen that, in two pressure stages in which the corresponding phases occur simultaneously, the following known relation must obtain:

$$\frac{p_2}{p_1} = \frac{p_1}{p_0}$$

In order that the areas of the force-stroke diagrams of the low-pressure and high-pressure stages be equal, a second relation, also well known, must obtain:

$$S_1 p_1 = S_2 p_2$$

These two relations insure the maximum efficiency in a two-stage compressor, and under these conditions, the low-pressure and high-pressure compressor pistons 3₁ and 3₂ are subjected on their working faces to equal and opposite total forces. Any unbalance in the aggregate forces acting on the opposed reciprocating groups of parts will therefore necessarily result from the fact that the rear, or inactive faces of compressor pistons 3₁ and 3₂ are subjected to unequal forces, which is the case when said inactive faces are subjected to the same pressure, such, for example, as that of the atmosphere.

According to one embodiment of the invention, 30 the auxiliary compensating cylinder 6 is adapted to compensate said unbalanced forces. In the case most commonly found in practice, where the inactive faces of compressor pistons 3₁ and 3₂ are subjected to atmospheric pressure, it may be shown that said unbalanced forces are accurately compensated when the area S_c of the auxiliary compensating piston 5 satisfies the following relation:

$$S_c = S_1 \frac{p_0}{p_1(p_0 + p_1)}$$

When the three relations mentioned above are satisfied, even through the motor-compressor unit is asymmetrical, the opposed reciprocating piston groups are subjected to equal and opposite forces at all points of the working cycle, and the synchronizing means interconnecting said reciprocating parts, such, for example, as connecting rods 12₁ and 12₂ and cranks 13, never have to transmit energy from one group to the other, which is the condition obtaining in symmetrical units.

Fig. 2 indicates the diagram a₁ b₁ c₁ d₁ of the total force S₁ p acting on the working face of the low-pressure compressor-piston 3₁; whereas line f₁ d₁ indicates the constant force exerted on the inactive face of said piston. Fig. 3 shows the diagram a₂ b₂ c₂ d₂ of the total force S₂ p exerted on the working face of the high-pressure compressor piston 3₂, whereas line f₂ g₂ shows the constant force acting on the rear or inactive face of said piston 3₂, which constant force is different from that acting on piston 3₁. The areas indicated in oblique cross-hatching in Figs. 2 and 3 represent the energy available for the return of the pistons. Fig. 4 shows a diagram f₁ d₁ f₂ g₂ which represents the difference between the areas f₂ g₂ d₂ a₂ b₂ and f₁ a₁ b₁, which difference must be added to f₁ a₁ b₁ in order to equalize at all points of the cycle the aggregate forces acting upon the reciprocating parts.

I attain this result:

By designing the compensating cylinder 6 so as to adapt it to compensate the unbalanced

forces acting on the reciprocating parts, so that the energy available from the first and second sources mentioned hereabove for the return of the pistons will always be sufficient to give the required final compression pressure in the combustion chamber, regardless of the length of the working stroke;

Preferably the compensating cylinder 6 is designed so as to adapt it to supply the energy required for the return stroke, while the equalizing of the forces acting in the opposed reciprocating assemblies is accomplished by applying to the inactive faces of the compressor pistons 3₁ and 3₂ suitable pressures, which may be above or below atmospheric pressure.

Motor-compressor units of the type in question operate on the two stroke cycle, and must therefore be provided with scavenging means. Said means may be provided by inclosing the space 9 between the low-pressure and high-pressure pistons 3₁ and 3₂ within a closed casing. It is evident that the alternating motion of said pistons periodically increases and reduces the volume of said inclosed space, which when provided with suction and discharge means, such as inlet valves 16, inlet ports 17 in the combustion chamber, and combustion outlet or exhaust 18 is adapted to act as a scavenging compressor. In this case, pistons 3₁ and 3₂ being both subjected to the scavenging pressure, said pressure has no tendency to upset the balance of forces.

It is also possible as shown in Fig. 5 to use as a scavenging pump a chamber 10 obtained by providing a gas-tight partition 11 closing the rear end of the low-pressure cylinder 4, thus making the low-pressure stage double-acting. Chamber 10 communicates with the atmosphere by valves 19 and with the other portion of casing 9 by valves 20. Under these conditions, the scavenging compressor would tend to unbalance the reciprocating parts; but this effect may be rendered negligible by subjecting the rear face of the high-pressure piston 3₂ to the delivery pressure of the scavenging unit; for example, by using the space 9, inclosed in the closed casing, as a scavenging air storage reservoir.

It should be understood that I do not wish to be limited to the structural details described and illustrated, for obvious modifications thereto will occur to persons skilled in the art.

What I claim is:

1. A two-stage internal-combustion free and opposed piston motor compressor unit, comprising a motor cylinder, two axially movable motive pistons in said cylinder, a combustion chamber between said motive pistons, a low-pressure compressor cylinder at one end of said motor cylinder, a high-pressure compressor cylinder at the other end of said motor cylinder, compressor pistons axially slidable within said low and high pressure compressor cylinders, rigid operative connections between one of said motive pistons and said low-pressure compressor piston, and between the other motive piston and said high-pressure compressor piston, conduit means interconnecting said low and high pressure compressor cylinders, and pneumatic means adapted to supply an amount of energy for the return stroke which is substantially independent of the length of the working stroke and to equalize substantially the aggregate forces acting on the oppositely reciprocating piston groups at least at one point of the working cycle, said pneumatic means comprising, in combination, a gas cushion inclosed in the clearance space of the low-pressure com-

pressor cylinder, a volume of partly compressed gas delivered by said low-pressure cylinder to said high-pressure cylinder, and an auxiliary compensating cylinder adjacent to, and in alignment with, said low-pressure compressor cylinder, an axially slidable compensating piston within said auxiliary cylinder, a rigid operating connection between said compensating piston and said low-pressure compressor piston, and means for introducing gas into said auxiliary compensating cylinder at the pressure of delivery from the high-pressure stage.

2. A two-stage motor-compressor unit according to claim 1, in which said means for introducing gas into said auxiliary compensating cylinders comprises a pipe permanently connecting said cylinder with the gas delivery from the high-pressure compressor cylinder.

3. A two-stage motor-compressor unit according to claim 1, in which the diameters of the motive pistons, of the high and low-pressure compressor pistons and of the auxiliary compensating piston, are so interrelated as to provide simultaneously an amount of energy for the return stroke which is substantially independent of the length of the working stroke, and to equalize the aggregate forces acting on the oppositely reciprocating piston groups at all points of the working cycle.

4. A two-stage motor-compressor unit according to claim 1, in which the initial suction pressure p_0 , the first stage delivery pressure p_1 , the second-stage delivery pressure p_2 , the areas S_1 of the first-stage compressor piston, S_2 of the second-stage compressor piston, and S_c of the auxiliary compensating piston, are so chosen as substantially to satisfy the following relations:

$$1 - \frac{p_2}{p_1} = \frac{p_1}{p_0}$$

$$2 - S_1 p_1 = S_2 p_2$$

$$3 - S_c = S_1 \frac{p_0}{p_1(p_0 + p_1)}$$

5. A two-stage motor-compressor unit according to claim 1, in which the space between the inactive faces of said low and high-pressure compressor pistons is inclosed in a closed casing and used as a scavenging gas compressor.

6. A two-stage motor-compressor unit according to claim 1, in which the low-pressure compressor cylinder is made double-acting and is adapted to compress gas on the return stroke for scavenging purposes.

7. A two-stage motor-compressor unit according to claim 1, in which the low-pressure compressor cylinder is made double-acting and is adapted to compress gas on the return stroke for scavenging purposes, and in which the space between the low and high-pressure compressor cylinders is inclosed in a closed casing and used as a scavenging air reservoir.

8. A multi-stage internal-combustion free and opposed piston motor-compressor unit comprising in combination a motor cylinder, axially movable motive pistons in said cylinder, a combustion chamber between said motive pistons, a compressor system of lower mean pressure having at least one compressor cylinder and one compressor piston at one end of said motor cylinder, a second compressor system of higher mean pressure having at least one compressor cylinder and one compressor piston at the other end of said motor cylinder, rigid operative connections between said motive pistons and said compressor pistons, respectively, and auxiliary compensating cushion

- means only on the side of the lower pressure compressor system, said compensating means comprising an auxiliary cylinder and an auxiliary slidable compensating piston in said cylinder, a 5 rigid operating connection between said compensating piston and the piston of the lower pressure compressor system and means for introducing gas in said auxiliary compensating cylinder at the pressure of delivery from a higher pressure stage.
- 10 9. A multi-stage motor-compressor unit according to claim 8, in which the pressure in said

auxiliary compensating means is substantially constant during the operation of the said compensating piston and equal to the pressure of a higher pressure stage.

10. A two-stage motor compressor unit, ac- 5 cording to claim 1, in which the pressure in said auxiliary compensating cylinder is substantially constant and equal to the delivery pressure of said high pressure stage.

RAUL PATERAS PESCARA. 10
